UNITED STATES PATENT OFFICE.

GEORGE G. FELT, OF WASHINGTON, DISTRICT OF COLUMBIA.

CAP ATTACHMENT FOR FOUNTAIN PENS.

Application filed December 8, 1925. Serial No. 74,068.

The present invention relates to a cap attachment for fountain pens and the like, and aims to provide a novel and improved device of this character whereby the cap will be at all times carried by the pen and may be conveniently moved and placed on either end of the pen, according to whether or not it is desired to use the pen, thus eliminating the danger of losing the cap as often occurs with pens now on the market.

Another object of the invention is to provide a device as above outlined comprising a pair of bars arranged on opposite sides of and pivotally connected to the pen and cap, said bars having their ends that are pivotally connected to the pen arranged for sliding longitudinally thereon and having yieldable means for normally returning or holding the ends of the bars pivoted to the pen approximately midway of the length of the pen, so as to yieldably hold the cap on either end of the pen.

It is also an object of the invention to provide a device of the above indicated character, which is simple and substantial in construction, which can be manufactured economically, which will not interfere with the efficiency of the pen, and which will be thoroughly efficient and practical in use.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawing, wherein:

Figure 1 is an elevation of my improved pen, showing the cap in various positions as indicated by dotted lines,

Figure 2 is a longitudinal section taken on line 2-2 of Figure 1,

Figure 3 is a cross section taken on line 3-3 of Figure 2, and

Figure 4 is a cross section taken on line 4-4 of Figure 2.

Referring to the drawing by numerals, the numeral 10 designates the barrel of the pen which carries a point 11 on one end and has positioned therein the usual ink retaining bag 12. The cap 13 for the pen has the usual spring clip 14 carried thereby for yieldably holding the pen in the pocket of its owner when not in use.

In carrying out my invention, the numeral 15 indicates a pair of longitudinal slots arranged in the barrel 10 and on opposite sides thereof, said slots extending practically the entire length of the barrel 10 of the pen. Positioned in the barrel 10 and secured at the slots 15 are cylinder members 16, which are provided with reduced neck portions 17 along the longitudinal sides thereof, said neck portions having the edges thereof turned over, as at 18, for securing the cylinder members 16 within the barrel 10. From the foregoing, it will be noted that the cylinder members 16 are provided with a reduced opening extending to the exterior of the barrel 10.

Arranged in each of the cylinders 16 is a head or piston 19, provided with a reduced extension 20 which extends through the reduced neck portion of the cylinders. Connected to each of the heads or pistons 19 is one end of a pair of bars 20', said bars having their ends which are connected to the heads or pistons 19 turned or bent at right angles, as at 21, and extending through openings 22 provided through the heads or pistons 19 and their reduced extensions 20. The ends of the angled portions 21 have heads 22' arranged thereon for preventing disengagement of the bars 20' from the heads or pistons 19.

Arranged in the cylinders 16 and upon both sides of both pistons or heads 19 are small coil springs 23, which abut against the heads or pistons 19 at one end and have their opposite ends abutting against end closing walls 24 provided upon the ends of the cylinders. From the foregoing it can be seen that the coil springs will normally hold the heads or pistons in positions approximately midway of the length of the cylinders against tension of the springs 23.

The opposite ends of the bars 20' are also turned at right angles, as at 25, and extend through a metallic band 26 arranged upon the cap 13, said right angled bent portions 25 also having heads 27 thereon for preventing disengagement of the bars 20' from the ring 26 and cap 13. It will be noted that the bars 20' each have one end thereof pivotally connected to the barrel of the pen while the opposite ends thereof are pivotally connected to the cap 13, so as to permit relative swinging movement of the cap with relation to the barrel of the pen.

In operation, the cap 13 may be positioned

upon either end of the barrel 10 of the pen, and by sliding the cap 13 away from the barrel 10 until the same is beyond the end of the barrel or the point 11 of the pen and 5 then swinging the cap to a position such as indicated by dotted lines in Figure 1, the cap may be swung around and moved to the opposite end of the barrel by exerting a pull on the cap against tension of certain of the coil springs 23. As soon as the cap is properly positioned at either end of the barrel 10 and released, the coil springs 23 will move the cap upon the barrel and hold said cap in such position. From the foregoing, it can 10 be seen that the cap is at all times carried by the barrel of the pen, thus eliminating the danger of losing the cap while changing the same from either end of the barrel.

Having thus described my invention, what 15 I claim as new is:

1. A device of the character described in combination with a pen and cap, comprising means slidably mounted on the pen and connected to the cap for permitting the cap 20 to be placed on either end of the pen.

2. A device of the character described in combination with a pen and cap, comprising a pair of bars each having one end thereof pivotally connected to the barrel of the pen 25 and the other end pivotally connected to the cap, and means for slidably supporting said pivotal connection of said bars on said pen so that said cap may be positioned upon either end of said pen.

3. A device of the character described in combination with a pen and cap, comprising members connecting said cap to said pen, and means slidably mounting said members on said pen.

4. A device of the character described in combination with a pen and cap, comprising a pair of bars, members slidably mounted upon said pen and pivotally connected to said bars, said bars being also connected to 45 said cap for permitting said cap to be placed upon either end of said pen.

5. A device of the character described in combination with a pen and cap, comprising a pair of members slidably mounted upon the pen, bars pivotally connected to said members at one end and at their other end pivotally connected to said cap, and spring means for normally holding said members intermediate the ends of said pen.

55 6. A device of the character described in combination with a pen and cap, comprising a pair of cylinders arranged on said pen, pistons slidably mounted in said cylinders, bars connected to said pistons and to said cap for permitting the placing of said cap on either end of said pen.

60 7. A device of the character described in combination with a pen and cap, comprising a pair of cylinders arranged on said pen, pistons slidably mounted in said cylinders,

bars connected to said pistons and to said cap for permitting the placing of said cap on either end of said pen, and coil springs arranged in said cylinders for normally holding said pistons intermediate the ends of 70 said cylinders.

8. A device of the character described in combination with a pen having slots arranged in the opposite sides thereof and a cap, of blocks slidably mounted in said slots 75 of said pen, and means connected to said blocks and to the cap for permitting swinging movement of the cap to either end of the pen.

9. A device of the character described in combination with a pen having slots arranged in the opposite sides thereof and a cap, of blocks slidably mounted in said slots of said pen, means connected to said blocks and to the cap for permitting swinging 25 movement of the cap to either end of the pen, and spring means for normally holding said blocks intermediate the ends of the slots for holding the cap on either end of the pen.

90 10. A device of the character described in combination with a pen having slots arranged in the opposite side walls thereof, a pair of cylinder members arranged in said pen and having openings to the exterior of 95 the pen, pistons mounted in said cylinders, bars pivotally connected to said pistons and extending through said openings leading to the exterior of the pen, and a cap pivotally connected to the opposite ends of said bars 100 so as to be placed upon either end of the pen upon sliding movement of the pistons and pivotal movement of the cap and bars with relation to the pen.

11. A device of the character described in combination with a pen having slots arranged in the opposite side walls thereof, a pair of cylinder members arranged in said pen and having openings to the exterior of the pen, pistons mounted in said cylinders, 110 bars pivotally connected to said pistons and extending through said openings leading to the exterior of the pen, a cap pivotally connected to the opposite ends of said bars so as to be placed upon either end of the pen 115 upon sliding movement of the pistons and pivotal movement of the cap and bars with relation to the pen, and coil springs arranged in said cylinders on each side of said pistons for normally holding the cap against 120 spring tension on either end of the pen.

12. A device of the character described in combination with a pen having longitudinal slots provided in the side walls thereof and a cap, cylinder members arranged in the 125 pen at said slots, members slidably mounted in said cylinders, a metallic member arranged upon said cap, and bars pivotally connected to said members in said cylinders and to said member on said cap so that said 130

cap will be carried by said pen and may be moved to either end of said pen.

13. A device of the character described in combination with a pen having longitudinal slots provided in the side walls thereof and a cap, cylinder members arranged in the pen at said slots, members slidably mounted in said cylinders, a metallic member arranged upon said cap, bars pivotally con-

nected to said members in said cylinders and to said member on said cap so that said cap will be carried by said pen and may be moved to either end of said pen, and spring means for yieldably holding the cap upon either end of the pen. 10 15

In testimony whereof, I have affixed my signature.

GEORGE G. FELT.
